CARD SHUFFLER AND TRAY

Albert J. Matter, Park Ridge, Ill.

Application March 22, 1954, Serial No. 417,544

8 Claims. (Cl. 273—149)

This invention relates to improvements in card shuffler and tray and has for its object to provide a simplified means for shuffling playing cards consisting of two or more regular decks such as Canasta, Samba or Bolivia.

Another object is to provide this in the form of a card tray so that it will serve as a combination tray and shuffler which can be formed of molded plastic for the purpose of appearance, compactness, economy of manufacture and with a minimum number of moving parts.

I attain these objects by means of the devices shown in the accompanying drawings in which:

Fig. 1 is a plan view of the assembled tray, slide bar and pressing levers.

Fig. 2 shows a front elevation of the same.

Fig. 3 shows a side elevation of the tray, partially in cross section through the center.

Fig. 4 is a side elevation of the slide bar.

Fig. 5 shows an end elevation of the slide bar.

Fig. 6 is a front elevation of a modified form of tray without a slide-bar or pressing levers.

Fig. 7 shows a plan view of the tray in Fig. 6.

Like numerals of reference indicate similar parts throughout the several views.

Referring to Figs. 1 and 7, it will be noted that cards are shown in place as being shuffled and by means of broken lines they are indicated in position for play.

At 1 is indicated a tray having inclined card supporting surfaces 1a which inclination tends to cause the lower adjacent corners of the cards indicated at 2a to overlap before the upper corners while being shuffled. Side walls 1b are provided for limiting outward movement of cards when stacked on edge for shuffling and have stop shoulders 1c to support the card deck ends when pressed back. 1d indicates two upright slide-bar guides formed as part of the said tray 1. The rear of the tray at 1e is provided with a T-shaped upright portion serving to provide a back stop at 1k for cards being shuffled and also provides a nest for holding the rear corners of stacked cards in place while in play.

For shuffling, cards are stacked on edge as indicated at 2, half of the deck on one side and half on the other side of the center. To press the cards back into shuffling position pressing levers are provided as shown at 3, preferably curved for ease of operation and provided with handles 3a. Levers 3 have metal pins 4 extending therefrom downwardly into holes 1f formed in tray 1 as shown in Fig. 2. Pins 4 may be rigidly fastened in levers 3 and rotatably free in holes 1f or vice versa.

5 is a slide band adapted to slide back and forth in groove 1g formed between uprights 1d and has inclined card edge contacting surfaces 5a and beveled upper edge 5b for easier insertion of the cards as indicated at 2. Slide bar 5 is also provided with a handle end at 5c, a lower sliding surface 5d and guide fin 5e terminating in an ear 5f perforated at 5g to hold a pin 6. Slide bar 5 is positioned in the tray 1 as indicated at 5h with its under surface 5d resting on a flat center surface 1h formed along the center of tray 1 and with fin 5e slidably held

2

in a groove 1i and slot 1j formed below the card supporting surface as shown in Fig. 3. Ear 5f of said slide extends through slot 1j so that cross pin 6 slidably holds slide-bar 5 in place.

5 In Fig. 1 levers 3 are shown in broken lines in the loading or playing position and in full lines in the positions they assume after pressing the cards out to the shuffling position indicated at 2b.

In operation, with levers 3 in the broken line positions 10 shown in Fig. 1, two groups of cards are placed on edge, and in a flat state, obliquely on opposite sides of the divider or slide bar 5; the divider being at the rear limit of its movement, with its rear end at 5i in Fig. 1. At this time the cards take the form of the parallelogram

15 2, appearing in broken lines in the right half of the tray in Fig. 1. Up to this time levers 3 were in the broken line positions shown in Fig. 1, but now they are swung to bring their curved, shoe-like parts into engagement with the cards. After such engagement has been effected

20 the swinging movements of the levers is continued until they reach the full line positions, where they must stop. Since the outer ends of the cards are held back by stops 1c, the inner ends slide back along the slide bar and the cards are compressed into a compact arc. At the

25 end of the movements of the levers the inner ends of the cards are still in engagement with the slide bar, although in Fig. 1 a few cards have already left the card separating end of the latter and have intermingled; this being due to the fact that in Fig. 1 the slide bar or divider has

30 already been drawn forward from 5i to 5j, broken lines 2b indicating the rearmost cards prior to drawing the divider forward. As the slide is caused to move forward, one card after another, in each group is released and springs past the center to overlap a corresponding card

35 in the other group.

Thus the work of stressing and releasing the cards comprises separate and distinct operations. The user may swing the levers as forcibly and as quickly as desired, because the cards can go no farther than the rear end 40 of the divider; and the cards are released upon the mere drawing forward of the divider.

This division of the work is important from another viewpoint. The stressing of the cards having been completed the curvature of the cards has been established and remains unchanged so long as any card remains in contact with the side of the divider. Were the divider stationary and the lever mechanism so constructed as to push all of the cards off at the rear end of the divider, the curvature of each card would become sharper than it was initially, as it approached the release point. In

50 other words, a tangent to any card at the point of contact with the divider would be at varying angles to the divider as it approached the release point. In the instant structure this angle never varies and is the same for all cards so long as they have not been released. Therefore, by

55 selecting the best angle, proper intermingling of the cards is ensured, because the angle does not vary and thus allow irregular riffling.

When the groups of cards are small, a fairly good shuffle can be made even with change in the angle at 60 which a card meets the divider at the release point. However, when the groups are large, the curvature of quite a few of the cards last to be released may be so sharp that the shuffle is spoiled.

After the cards have all slipped off at the front end of the retreating divider, they are removed from the tray and manipulated to transform the two groups into a single group or pack; thereby completing the shuffle.

After shuffling, the tray may be used as a regular 70 canasta or samba tray by placing the levers as shown in broken lines in Fig. 1 and stacking cards as indicated

at 2d. To indicate "frozen" discards, the "freeze" card can be placed as shown at 2e.

I have discovered that for shuffling two regular card decks or less very satisfactory results are obtained without a sliding center divider or levers, as shown in the modified form in Figs. 6 and 7 wherein tray 1 is provided with an integral dividing wall 11 having an end 1m past which the cards can be pressed by hand as shown in Fig. 7 and they will intermingle as indicated at 2c. This tray likewise can be used for play as well as for shuffling. Altho the tray shown in Figs. 6 and 7 has a flat upper surface this can also be inclined as shown in Fig. 2 making it easier to overlap the lower corners.

In this type of shuffler all cards after shuffling remain faced just as placed in position and will not turn over as sometimes occurs in crank and roller types. The action is similar to hand shuffling in that it varies and is irregular in spacing of card groups depending on the action of different individuals, the overlapping cards being either singles or groups of 2 or more and will vary from time to time with the same person. It however gives much greater control of mixing and greatly simplifies shuffling two or more decks at one time.

What is claimed is:

1. In a card shuffler, a tray having thereon a central divider movable between a rearward limit and a forward limit, with its rear end being a card separating end, card retaining walls on the tray on opposite sides of the divider and having toward their rear forwardly facing stops, the parts being so proportioned that when two groups of cards are placed on edge between the stops and the divider they are oblique to the latter and contact the same at such a distance from said separating end that the cards of each group receive their final stressing when compressed rearwardly into a compact arc and all cards are still engaged with the divider, whereby each card is automatically released upon moving the divider forward; and lever devices mounted on the front portion of the tray for movements adapted to press all of the cards into their final arc shapes before any card is released as aforesaid.

2. In a card shuffler, a tray having thereon a central divider in the form of a slide movable between a rearward limit and a forward limit, with its rear end being a card separating end, card retaining walls on the tray on opposite sides of the divider and having toward their rear forwardly facing stops, the parts being so proportioned that when two groups of cards are placed on edge between the stops and the divider they are oblique to the latter and contact the same at such a distance from said separating end that the cards of each group receive their final stressing when pressed rearwardly into a compact arc with the rearmost cards still engaged with the divider, whereby each card is automatically released upon moving the divider forward, and means at the front of

and movable independently of the slide on the tray to press the cards rearwardly only far enough to create and maintain such arc until released as aforesaid.

3. A card shuffler as set forth in claim 2, wherein the bottom of the tray contains a groove and the divider fits slidably in said groove.

4. A card shuffler as set forth in claim 2, having at the rear a central, stationary stop for the cards, such stop being spaced apart from the stops on the card retaining walls at least as far as the width of a card, so that the cards may be laid flat in each side of the tray with their long axes parallel to or making a small angle with the divider and with the cards protruding beyond a line connecting the central stop with the corresponding stop on the said walls.

5. A card shuffler as set forth in claim 2, wherein the means for pressing the cards rearwardly are movable between a rearward limit corresponding to the completion of the compact arc and a forward position clear of cards lying flat in the tray parallel to the divider.

6. In a card shuffler, a tray having a central divider movable between a rearward limit and a forward limit, with the rear end being a card separating end, card retaining walls on opposite sides of the divider and having toward their rear forwardly facing stops, the parts being so proportioned that when two groups of cards are placed on edge between the stops and the divider they are oblique to the latter and contact the same at such a distance from said separating end that the cards of each group receive their final stressing when pressed rearwardly into a compact arc while so engaged with the divider, whereby each card is automatically released upon moving the divider forward, a pair of levers mounted on the front portion of the tray, one on each side of the divider, for swinging movements about vertical axes, each lever being shaped at one end to engage the cards while the other end constitutes a handle for operating the same.

7. A card shuffler as set forth in claim 6, wherein the levers may swing into idle positions so as to leave the area of the bottom of the tray behind them, clear of obstructions and thus permit cards to be stored in the tray or take various playing positions in the tray.

8. A card shuffler as set forth in claim 7, wherein there are stops on the tray to limit card pressing movements of the levers to the points at which the final stressing of the cards occurs.
